UNITED STATES PATENT OFFICE

157,641

TRIMMING OR SIMILAR ARTICLE

Herman Stern, New York, N. Y.

Application October 7, 1949, Serial No. 5,343

Term of patent 3½ years

(Cl. D3—32)

To all whom it may concern:

Be it known that I, Herman Stern, a citizen of the United States of America, residing in the Borough of Manhattan, city of New York, county of New York, and State of New York, have invented a new, original, and ornamental Design for a Trimming or Similar Article, of which the following is a specification, reference being had to the accompanying drawing, forming a part thereof.

The figure is a plan view of a piece of a trimming, showing my new design.

A design unit is shown between the dot-dash lines and is repeated as indicated.

I claim:

The ornamental design for a trimming or similar article, as shown and described.

HERMAN STERN.
